UNITED STATES PATENT OFFICE.

THEOPHILUS BROWN, OF MOLINE, ILLINOIS, ASSIGNOR TO DEERE & COMPANY, OF MOLINE, ILLINOIS, A CORPORATION OF ILLINOIS.

PLOW.

Application filed May 20, 1920. Serial No. 382,913.

My invention relates to improvements in plows and the object of the invention is the provision of improved means for effecting the raising and lowering of the plow.

5 A preferable embodiment of my invention is shown in the accompanying drawing, wherein like numerals of reference refer to similar parts in the several views.

In the drawings—
10 Figure 1 is a plan view of the improved plow.

Figure 2 is a side elevation of the plow in raised position.

15 Figure 3 is a side elevation, but with the plow in lowered position.

Figure 4 is a section on the lines 4—4 of Figure 1.

Referring to the drawings, the frame of the plow is in the form of a beam structure 20 that comprises the plow beams 5, 6, and 7 spaced apart and connected by braces 8, 9, 10 and 11 bolted or otherwise rigidly secured thereto. A plow body 12, constituting a plow unit of a well known type, is carried 25 by each of the beams 5, 6 and 7. A crank axle 13 is rockably journaled in bearings 14 and 15, supported by the beams 5 and 6 respectively, and extends forwardly and downwardly, and on the outer end thereof is 30 mounted a furrow wheel 16. A crank axle 17 is rockably journaled in bearings 18 and 19, secured to the beams 5 and 7 respectively, and extends forwardly and downwardly terminating in an inwardly extending spindle 20, on which is mounted a landwheel 21.

The plow at its rear is supported in the following manner: Mounted on opposite sides of the rear of the beam 7 are members 22, between which a lever 23 is pivotally 35 supported intermediate its ends, the lower end of the lever being pivotally connected with the bifurcated end of a sleeve 24 in which is journaled a spindle 25 preferably integral with a crank axle 26 on the laterally 40 extending portion 27 of which is mounted a rear furrow wheel 28. The sleeve 24 is pivotally connected intermediate its length to links 29 which are pivoted on opposite sides of the beam 7.

45 Rigidly secured to the axle 17 is an up- standing arm 30, to the upper portion of which is pivotally connected a rod 31 that extends rearwardly and is slidably supported in a sleeve 32, the latter being pivot- 50 ally connected to the upper end of the lever

23. Adjustable stops 33 on the rod 31 on opposite sides of the sleeve 32 limit the sliding movement of the rod 31.

Rigidly secured to the axle 13 is an up- 55 standing arm 34, to the upper end of which is pivotally connected a bar 35 that extends rearwardly and is pivotally connected with the arm 30.

It will thus be seen that if the axle 17 is 60 rocked back and forth in its bearings the arm 30 will be oscillated and by reason of the connections 31 and 35, movement will be 65 imparted to the lever 23 and the arm 34, which will swing the furrow wheels and act in conjunction with the rocking of the land- 70 wheel to bodily raise or lower the beams in unison dependent upon the direction in which the axle 17 is rocked.

Plows of this type are usually tractor 75 drawn, but may also be horse drawn and the numeral 36 indicates a tractor drawbar or the animal draft device, provided with the customary provision for transverse adjustment of the plow hitch, which in this instance comprises bars 37 and 38 that are 80 pivotally connected with the draw bar or draft device at their forward ends and are pivotally connected at their rear ends with a transversely positioned hitch member 39 carried by the plow in a manner that will 85 be hereinafter described,—the hitch member 39 being provided with a plurality of holes to accommodate the adjustment of the draft members 37 and 38 transversely thereof.

In plows of this class the depth of plow- 90 ing is principally regulated by the vertical adjustment of the landwheel and the front furrow wheel relatively to the plow beams.

In the structure illustrated, the bearing 14 for the furrow wheel crank axle 13 is pivot- 95 ally supported at 39^a upon a bracket 40 se- cured to the beam 5, the bearing 14 having secured to it a lever 41, by means of which the bearing 14 can be swung about the pivot 100 39 carrying with it the crank axle 13, the bearing 15 during such adjustment acting as the fulcrum for the axle 13. The lever 41 is held in its various positions of adjust- 105 ment by a notched rack 42, the lever carry- ing the usual spring actuated locking dog indicated at 43, which engages with the notches in the rack, the dog being operated by the usual hand latching mechanism in- 110 dicated at 44.

The plowing position of the landwheel 21 is regulated by a lever 45 pivotally mounted at 46 upon a bracket 47 secured to the brace member 10, the lever 45 having an arm 48, that carries a pin or bolt 49 that slides freely in a slot 50 formed in a bar 51 that at its lower extremity is journaled on the spindle 20 of the land wheel axle 17. The lever 45 is held in its various positions of adjustment by a notched rack 52, the lever carrying the usual spring actuated locking dog indicated at 53 which engages with the notches in the rack, the dog being operated by the usual hand latching mechanism indicated at 54.

It will be seen that the pin 49 on the arm of the lever 45 cooperates with the slotted bar 51 to limit the depth to which the plows will penetrate, since when the plows are lowered to operative position the pin 49 serves as an adjustable abutment on the plow frame that is adapted to take the thrust of a stop on the axle 17, in the form of that portion of the bar 51 at the lower end of the slot 50, and resist swinging of the land wheel axle in a direction to permit descent of the frame, that is to say toward the frame, beyond the level established by the position of the pin 49. To level the plow to the new depth thus established by the land wheel, the operator should stroke the lever 41 to lift the furrowwheel side of the plow relatively to the furrowwheel 16.

The force utilized to raise the plow from working position to transport position is the drawing power of the tractor or draft animals acting against an abutment engaging with the ground, such as that furnished by the plow bodies or a locked wheel. The forces utilized to return the plow to working position are gravity; the suck of the plow body seeking its working depth in response to the bend in the draft line, due to the elevation of the plow; and the drawing power of the tractor or draft animals acting against an abutment engaging with the ground, such as that furnished by the plow bodies as they enter the ground, such latter force being utilized to swing the landwheel and furrowwheel axles in their bearings and load the weight of the wheels mounted thereon upon the beams, such latter force acting within the limits established by the relationship of the stop 49 and the slot 50.

These forces are brought into play and utilized by the means now to be described.

The beams 5 and 6 at their forward ends are connected by a heavy rod bolt 55 upon which is pivotally mounted a rocking member 56, the latter as best seen in Figures 1 and 2, having a pair of upwardly and rearwardly inclined arms 57, said arms with the member 56 forming a rocking support on which is pivotally supported a crank draft element in the form of a transverse member

58 having arms 59, to the free ends of which arms are pivotally secured vertically swinging clevises 60 that connect with and carry the transverse hitch member 39. To the draft element 58 is rigidly secured a lever 61, the latter having the usual hand latch operating means 62 that operates a spring actuated locking dog 63, carried by the lever, which engages with recesses formed in a lever rack 64 secured to the rocking support 56. In this manner the rocking support 56 and the parts carried by it will, as an entirety, swing around the pivot bolt 55; or if the lever be stroked, the crank draft element 58 will be rotated in its supports 57 and the arms 59 swung relatively to the rocking support 56.

The normal relationship of the several pivot points is such that when the lever 61 is in one position of adjustment relative to its rack, the draft force transmitted through the draft members 37 and 38 and the hitch member 39 will act to swing the rocking support 56 and its parts in one direction, and when the lever 61 is in the opposite position of adjustment on its rack, the draft forces act to swing the rocking support and its parts in the opposite direction. This swinging action of the rocking support is transmitted to the wheel system of the plow through the medium of a link 65 that at its forward end is pivotally connected with an upstanding arm 66 carried by the rocking support 56, the link at its rearward end being pivotally connected with the arm 30 secured to the axle 17. One of the arms 59 of the crank draft element 58 has connected to it a cable 67 that extends around the axle 17 and is secured to a dog 68 pivotally mounted on an arm 17a carried by the axle 17, the dog, in certain instances, as herein-after described, being actuated by the draft element 58 and cable 67 to engage with a toothed member 69 secured to the land wheel 21 to lock the landwheel from rotating about the spindle 20. The dog 68 is weighted so that in certain positions it normally acts by gravity to swing free of the teeth of the member 69. The dog 68 is also connected with the frame of the plow by a cable 70 so that a predetermined movement of the axle 17 in its bearings will positively disengage the dog 68 from the ratchet member 69. 71 indicates a locking member pivotally mounted at 72 upon a bracket 73 carried by the plow beam 6 and its brace 9. The member 71 is provided with a recess 74 which is adapted to engage with the end of the arm 30, when the plow is lifted, and lock the axle 17 against movement in its bearings. A spring 75 acts to press the locking member 71 downwardly and hold it securely in engagement with the member 30.

A bell crank 76 pivotally mounted at 77 upon the beam 6 is provided for lifting the

locking member 71 to release it from engagement with the member 30 when it is desired to lower the plow. As best seen in Figure 4, one arm of the bell crank lever extends under the free end of the locking member 71, the other arm of the bell crank lever being connected by a cable 78 to the lever 61, therefore when the lever 61 is stroked forwardly the bell crank 76 is actuated to pry 10 the locking member out of engagement with the arm 30.

Assuming the plow to be in the position shown in Figure 2 and that it is desired to lower the plow, the operator grasps the lever 15 61, unlocks it from the rack 64 and strokes it forwardly to the position indicated in dotted lines in said figure, locking the lever again to the rack. Such movement of the lever rocks the crank draft element 58 in its bearings on the rocking support 56, and swings 20 the arms 59 and the hitch members into the position indicated in dotted lines, which it will be noted is below the pivot 55. The stroking of the lever, through the cable 78, 25 has also actuated the bell crank 76 and disengaged the locking member 71 from the arm 30. As the plow settles, due to its weight, the landwheel and front furrow wheel axles rock forwardly and the rear furrowwheel rocks rearwardly until the plow 30 bodies engage the soil. During this movement the support 56 has also rocked to some extent on its pivot 55, owing to the link connection 65 with the arm 30. When the plow 35 bodies contact with the ground, they act as an abutment against which the draft force operates and as the line of draft is below the pivot 55 the draft force acts to rock the support 56 rearwardly about its pivot 55. This 40 rocking movement of the support 56 is communicated through link 65 to the arm 30 which is stroked rearwardly and acts to rock the landwheel forwardly and upwardly, the furrowwheels being simultaneously rocked 45 by reason of connections 31 and 35.

The force of the draft pulling directly against the plow bodies is therefore utilized to relatively swing the wheels upwardly and depress the beams until the lower end of the 50 slot 50 engages the stop 49, thereby preventing further movement toward each other of the frame and land wheel axle member after the plow bodies reach a predetermined depth, consequently the plows penetrate the 55 soil and reach their working depth very quickly.

Assuming the plow is in position for operation at the greatest depth it is designed to penetrate, as indicated in Figure 3, and 60 that it is desired to lift the plow, the operator grasps the lever 61, unlocks it from the rack 64, and thrusts the lever rearwardly to the position indicated in dotted lines, locking it again to the rack. This stroke of the 65 lever rocks the crank draft element 58 in its

bearings on the rocking support 56 and swings the arms 59 and the hitch member carried thereby, into the position indicated in dotted lines in Fig. 3, which it will be noted is above the pivot 55. The force of the draft pulling against the plow bodies will now act to rock the support 56 forwardly about its pivot 55, or in a counter-clockwise direction as viewed in said figure, and by reason of the link connection 65 to the 70 arm 30 the latter will be rocked forwardly, thus acting to lift the plows upwardly relatively to the wheels, the stop 49 moving away from the lower end of the slot 50 as this occurs. Simultaneously with the thrusting of the lever 61 rearwardly and the rocking of the arms 59 upwardly to the dotted line position, the arc described by the throw of the arms 59 acts to tighten the cable 67 and swing the dog 68 into engagement with 75 the tooth member 69, so that the locked landwheel serves as an abutment for the draft forces to pull against to raise the plow after the plow bodies have cleared the ground surface. It will be noted that in 80 lifting there is a relative forward movement of the draft devices as regards the frame, and a corresponding relative rearward movement in lowering.

The draft force in this manner raises the 85 plow until the arm 30 drops in the recess 74 of the locking chamber 71, simultaneously with which the cable 70 becomes taut and swings the dog 68 out of engagement with the tooth member 69 whereupon the plow 90 will be held in elevated position relative to the wheels until the lever 61 is again actuated to release the locking member 71 from the arm 30 and shift the draft device into 95 position for the draft force to cause the plow 100 to enter the soil.

If, when the lever 61 is stroked to lift the plow, the dog 68 should engage the tip of one of the teeth on the member 69, the spring 79 interposed between the arm 59 105 and the cable 67 will yield sufficiently to permit the lever to be locked to its rack and will press the dog against the toothed member. The spring 79 will also yield as the cable 70 swings the dog 68 out of engagement 110 with the toothed member at the completion of the lifting movement.

The rack 64 may be provided with a plurality of notches for the lever 61, as indicated at 80, to enable the operator to regulate the working position or vertical elevation of the arms 59 and the draft hitch member 39 carried thereby, relative to the 115 plow.

What I claim is—

1. A plow comprising a beam structure and a plow body carried thereby, land and furrow wheels, cranks connecting said wheels with the beam structure, and draft means operatively connected with the plow 120 130

and arranged to be manually shifted to apply the force of forward draft along a line optionally to either raise or lower the plow body.

- 5 2. A plow comprising a beam structure and a plow body carried thereby, land and furrow wheels, cranks connecting said wheels with the beam structure and adapted to rock to move the plow body and beam structure vertically relatively to the wheels, and draft means operatively connected with the plow and arranged to apply the force of forward draft in a direction to rock said cranks either to raise or to lower the plow body optionally.

3. A plow comprising a beam structure and a plow body carried thereby, land and furrow wheels, cranks connecting said wheels with the beam structure and adapted to rock to move the plow body and beam structure vertically relatively to the wheels, draft means operatively connected with the plow and arranged to apply the force of forward draft in a direction to rock said cranks either to raise or to lower the plow body, and means for optionally controlling the direction in which said cranks are rocked by the force of the draft.

4. A plow comprising a beam structure and a plow body carried thereby, land and furrow wheels, lifting means adapted to be actuated to move the plow body and beam structure vertically relatively to the wheels, draft means, swinging optionally controlled means interposed between said draft means and said lifting means and means operable to swing said swinging means to apply the force of the forward draft to said lifting means in a direction either to raise or to lower the plow body.

5. A plow comprising a beam structure and a plow body carried thereby, land and furrow wheels, cranks connecting said wheels with the beam structure and adapted to rock to move the plow body and beam structure vertically relatively to the wheels, draft means, optionally controlled means interposed between said draft means and said cranks, and means operable to adjust said optionally controlled means to apply the force of the forward draft to said cranks in a direction either to raise or to lower the plow body.

6. In a plow, the combination with a frame carrying a plow body, said frame provided with a movable wheel support, of draft means supported by the frame, shiftable means connecting said draft means with the wheel support whereby the force of the forward draft acts to rock said wheel support to move the frame vertically to vary the direction in which said wheel support is rocked by the draft, and means for locking the wheel support and frame when the plow is raised.

7. In a plow, the combination with a frame carrying a plow body, said frame provided with a movable wheel support, of draft means supported by the frame, shiftable means connecting said draft means with the wheel support whereby the force of the draft acts to move said wheel support to vary its position relative to the frame and thereby raise or lower the frame, means operable to adjust said shiftable means to control the direction of said movement, means to limit said movement and lock the wheel support and frame when the plow is raised, and a stop to limit said movement when the plow is lowered.

8. In a plow, the combination of a frame carrying a plow body, an axle movably mounted on the frame, a wheel on the axle, means for locking the wheel to the axle, draft means supported by the frame, shiftable means connecting said draft means with the axle whereby the force of the draft transmitted through said means acts to move said axle to raise or lower the frame, means operable to adjust said shiftable means to control the direction of said movement, and a connection between the wheel locking means and the draft means whereby the wheel lock is closed when said shiftable means is operated to apply the draft force to move the axle to raise the frame.

9. In a plow, the combination of a frame carrying a plow body, an axle movably mounted on the frame, a wheel on the axle, means for locking the wheel to the axle, draft means supported by the frame, shiftable means connecting said draft means with the axle whereby the force of the draft transmitted through said means acts to move said axle to raise or lower the frame, means operable to adjust said shiftable means to control the direction of said movement, a connection between the wheel locking means and the draft means to close the wheel lock when said shiftable means is operated to apply the draft force to the axle to raise the frame, and means to open said wheel lock when the frame is raised.

10. In a plow, the combination of a frame carrying a plow body, an axle movably mounted on the frame, a wheel on the axle, means for locking the wheel to the axle, draft means supported by the frame, shiftable means connecting said draft means with the axle whereby the force of the draft transmitted through said means acts to move said axle to raise or lower the frame, means operable to adjust said shiftable means to control the direction of said movement, a connection between the wheel locking means and the draft means to close the wheel lock when said shiftable means is operated to apply the draft force to the axle to raise the frame, means to open said wheel lock when the frame is raised, and a locking de-

vice carried by the frame and adapted to engage the axle to hold the frame in its raised position.

11. In a plow, the combination of a frame carrying a plow body, a movable wheel support for the frame, draft means supported by the frame, shiftable means connecting said draft means with the wheel support whereby the force of the draft acts to move 5 said wheel support to vary its position relative to the frame and thereby raise or lower the frame, means operable to adjust said shiftable means to control the direction of said movement, a locking device carried by 10 the frame and adapted to engage the wheel support when the frame is raised to hold the latter in its raised position, and a connection between said locking device and said shiftable means whereby the operation of the 15 latter to apply the draft force to lower the frame will open the lock.

12. A plow comprising a beam structure and a plow body carried thereby, land and furrow wheels, the beam structure being supported by said wheels and being movable 25 vertically relatively thereto, draft means operatively connected with the plow and arranged to apply the force of forward draft along a line either to raise or to lower the beam structure, and means for positively locking the beam structure in its raised position.

13. A plow comprising a frame carrying a plow body, wheels by which the plow body 35 is supported and with relation to which it is movable vertically, draft means operatively connected with the plow and arranged to apply the force of forward draft along a line to raise the plow body relatively to 40 said wheels, and means operable to impede the forward movement of the plow when the force of the draft is applied to raise the plow body.

14. A plow comprising a frame carrying a 45 plow body, wheels by which the plow body is supported and with relation to which it is movable vertically, draft means operatively connected with the plow and arranged to apply the force of forward draft along a 50 line to raise the plow body relatively to said wheels, and means for resisting forward rotation of one of said wheels when the force of the draft is applied to raise the plow body.

15. A plow comprising a beam structure and a plow body carried thereby, land and furrow wheels, the beam structure being movable 55 vertically relatively to said wheels, draft means operatively connected with the plow and arranged to apply the force of forward draft along a line to raise the beam structure relatively to the wheels, and means for resisting rotation of one of said wheels when the beam structure is being raised.

16. A plow comprising a beam structure

and a plow body carried thereby, land and furrow wheels, the beam structure being supported by said wheels and being movable vertically relatively thereto, draft means operatively connected with the plow and arranged to apply the force of forward draft along a line either to raise or to lower the beam structure, and means actuated when the force of the draft is applied to raise the beam structure for resisting rotation of 75 one of said wheels.

17. A plow comprising a frame carrying a plow body, wheels by which the plow body is supported, and with relation to which it is movable vertically, and means for applying the force of the forward draft to raise or lower the plow body relatively to the wheels comprising a rocking support pivotally mounted on the frame, a crank draft element pivotally mounted on said rocking support and adapted to swing therewith, draft means connected with said crank draft element and movable by the rocking thereof to carry the line of draft above or below the axis of said rocking support, and optionally controlled means for so rocking said crank draft element, and for locking the latter relatively to the rocking support so that they will swing in unison about the axis of said support.

18. In a plow the combination of a beam carrying a plow body, a crank axle pivotally connected with the beam, a wheel on said axle, means adapted to be actuated to lock the wheel and axle against relative rotation, draft means, means operatively connecting said draft means with the plow and operable to apply the force of forward draft to rock the crank axle to raise or lower the plow body, means for locking the plow body in 100 its raised position, and optionally controlled means for changing the line of draft from a lifting to a lowering position, or vice versa, and operable to release the locking means when said optionally controlled means is operated to lower the plow body.

19. In a plow the combination of a beam carrying a plow body, a crank axle pivotally connected with the beam, a wheel on said axle, means adapted to be actuated to lock the wheel and axle against relative rotation, draft means operatively connected with plow and arranged to apply the force of forward draft to raise or lower the plow body, a second locking means for holding the plow 115 body in its raised position, optionally controlled means for changing the line of draft from a lifting to a lowering position, or vice versa, and means for actuating said first-mentioned locking means to lock the 120 wheel and axle against relative rotation when said optionally controlled means is operated to cause the force of the draft to raise the plow body, and to release said second locking means when said optionally controlled 130 means is operated to lower the plow body.

trolled means is operated to cause the force of the draft to lower the plow body.

20. In a plow the combination with a plow body carrying frame, said frame being provided with a wheel support arranged to rock relatively to the frame to move the same vertically, of draft means supported by the frame and connected with the wheel support to apply the force of the forward draft to rock said wheel support, and means operable to apply the force of the forward draft to rock said wheel support optionally in either direction.

21. In a plow the combination with a plow body carrying frame, said frame being provided with a wheel support arranged to rock relatively to the frame to move the same vertically, of draft means supported by the frame and connected with the wheel support to apply the force of the forward draft to rock said wheel support, and means operable to optionally vary vertically the line of draft to effect the rocking of said wheel support in either direction by the force of the forward draft.

22. In a plow the combination with a plow body carrying frame, said frame being provided with a wheel support arranged to rock relatively to the frame to move the same vertically, of draft means supported by the frame to move fore and aft relatively thereto, and connected with the wheel support to apply the force of the forward draft to rock the same, and means operable to apply the force of the forward draft to rock said wheel support in either direction.

23. In a plow the combination with a plow body carrying frame, of swinging crank axle members supporting said frame, land and furrow wheels carried by said axle members, means operable to swing said axle members relatively to the frame to move the frame vertically, and depth regulating means comprising a thrust member connecting said frame and one of said axle members acting to prevent movement toward each other of the frame and such axle member when the plow body has been lowered to a predeter-

mined operative position, and means for varying the effective length of said connection.

24. In a plow, the combination with a plow body carrying frame, of swinging crank axle members supporting said frame, land and furrow wheels carried by said axle members, devices operable by the forward travel of the plow to lift said frame, and depth regulating means comprising a slotted bar connected with one of said axle members, and an adjustable lever mounted on said frame and having a stop movable in the slot of said bar.

25. In a plow the combination with a plow body carrying frame, of swinging crank axle members supporting said frame, land and furrow wheels carried by said axle members, means operable to swing said axle members relatively to the frame to move the frame vertically, and depth regulating means comprising a slotted bar connected with one of said axle members, and an adjustable lever mounted on said frame and having a pin movable in the slot of said bar and cooperating therewith to limit movement toward each other of the frame and such axle member when the plow body has been lowered to a predetermined operative position.

26. In a plow the combination with a plow body carrying frame, of a rocking wheel support for said frame comprising cranks, land and furrow wheels carried by said cranks, draft means, shiftable means supported by the frame and connected with one of said cranks to apply the force of the forward draft to rock the wheel support to move the frame vertically in either direction, and depth regulating means comprising an adjustable abutment on the frame, and a thrust connection carried by one of said cranks and connected with said abutment, to prevent movement toward each other of the frame and such crank when the plow body has been lowered to a predetermined operative position, and means for varying the effective length of said connection.

THEOPHILUS BROWN.

CERTIFICATE OF CORRECTION.

Patent No. 1,613,693.

Granted January 11, 1927, to

THEOPHILUS BROWN.

It is hereby certified that error appears in the printed specification of the above numbered patent requiring correction as follows: Page 1, line 101, for the numeral "39" read "39a"; page 4, line 61, claim 6, after the word "vertically" insert the words "means operable to shift said shiftable means"; and that the said Letters Patent should be read with these corrections therein that the same may conform to the record of the case in the Patent Office.

Signed and sealed this 26th day of April, A. D. 1927.

M. J. Moore,
Acting Commissioner of Patents.

Seal.
